UNITED STATES PATENT OFFICE.

EDMUND R. BARANY, OF BROOKLYN, NEW YORK, ASSIGNOR TO YALE ELECTRIC CORPORATION, A CORPORATION OF NEW YORK.

SAFETY SWITCH.

Application filed August 22, 1922. Serial No. 583,515.

To all whom it may concern:

Be it known that I, EDMUND R. BARANY, a citizen of the United States, and a resident of the borough of Brooklyn, county of 5 Kings, city and State of New York, have invented certain new and useful Improvements in Safety Switches, of which the following is a specification.

This invention relates to safety switches 10 particularly adapted to be used in connection with flashlights although not restricted to such use.

In flashlight constructions it is customary to employ a slidable switch actuating 15 member which is adapted to so engage a protruding lug as to effect a closing of the switch and consequently a closing of the electric circuit through the flashlight lamp.

One of the principal objections of such 20 construction resides in the fact that the protruding lug is often, when the flashlight is not in use, accidentally or otherwise depressed and maintained in circuit closing position a sufficient length of time to de- 25 stroy the activity of the flashlight battery and thus render the same useless.

An important object of my invention is to provide, in combination with a circuit closer, a means whereby the circuit is main- 30 tained open should the protruding lug, above referred to, become accidentally or otherwise depressed while the circuit closer actuating means is maintained in a normal or inoperative position.

35 A further object of my invention is to provide a switch particularly adapted to be used in connection with the flashlight which is simple in construction, reliable in operation and inexpensive to manufacture.

40 Other objects and certain advantages of the invention will become apparent from the following description when taken in connection with the accompanying drawings, in which—

45 Figure 1 is an elevation of a portion of a flashlight embodying my invention.

Figure 2 is a central longitudinal sectional view through a flashlight showing in section the several cooperative elements of 50 the switch embodying my invention.

Figure 3 is a transverse sectional view taken on line 3—3 of Figure 1.

In the drawings wherein for the purpose of illustration is shown what I at present 55 consider the preferred form of my inven-

tion the numeral 5 indicates a flashlight casing of usual metallic type, to the upper end of which is connected a reflector head 6, provided with a reflector 7 and having associated therewith a conventional form of 60 lens 8 which is mounted together with the reflector 7 in a proper position with respect to the head 6 by means of a lens ring 9. Within the casing 5 I have shown a conventional type of battery 10 adapted to furnish 65 electrical energy to a lamp 11, the screw threaded portion 12 of which is carried by a sleeve 13 formed integral with a metallic plate 14 which is supported by a fiber disc 15 arranged within the lower end of the 70 reflector head 6. Adjacent the plate 14 there is arranged a fiber disc 16 having an opening 17 adapted to receive a central contact 18 of the lamp 11 in order that the same may electrically engage a conductor 75 plate 19 electrically connected with a conductor arm 20 adapted to engage the central electrode 21 of the battery 10.

To the metallic plate 14 there is connected an insulated conductor 22 one end of 80 which is connected to a fiber plate 23 by means of a rivet 24. The fiber plate 23 is arranged within a shallow pocket or seat 25 formed in the casing 5 and is adapted to be retained in position by means of a housing 26 suitably connected to the casing 5 by 85 means of rivets or the like 27. Upon the housing 26 there is arranged a switch actuating slide 28 provided with oppositely disposed ears 29 extending through parallel 90 slots 30 formed in the housing. These ears serve not only as a means for retaining the slide 28 in position upon the housing 26 but function also as a means for so connecting the cam member 31 to the slide as to cause 95 the same to move therewith when the same is actuated. As is most clearly shown in Figure 3 the cam member is provided with oppositely disposed notches or the like 32 adapted to receive the ears 29 when the 100 switch is assembled.

Within the housing member there is arranged a more or less resilient circuit closer, indicated as a whole by the numeral 33, which is connected intermediate its ends to 105 the fiber plate 23 by means of a rivet 34 which is also passed through a fiber plate or washer 35, functioning with the plate 23 as a means for clamping the free end of the conductor 22 in such a position as to fa- 110

cilitate its cooperation with the circuit closer 33 as will hereinafter be more readily appreciated.

The circuit closer member 33, at one end, 5 is bent to provide an auxiliary circuit closer in the form of a resilient arm 36 adapted to engage the metallic casing 5 when the slide 28 is so moved as to effect a cooperation between the cam member 31 and the arm 10 36. The opposite end of the circuit closer member 33 is provided with a knob or lug 37 which protrudes through an opening 38 formed in the housing 26 and is further provided with a main circuit closer in the 15 form of a resilient arm 39 adapted to engage the conductor 22 when the slide 28 is so moved as to effect a depression of the lug 37.

With the several elements of the device 20 embodying my invention positioned as shown in Figure 2 it is obvious that if the lug 37 is so depressed as to move the arm 39 into engagement with the conductor 22 the circuit through the lamp 11 will not be 25 closed but if the slide 28 is so moved as to cause a depression of the lug 37 the circuit through the lamp 11 will be completed since such a movement of the slide 28 will cause the arm 36 to move into electrical engagement 30 with the receptacle 5 which is grounded to the battery 10 in the usual manner. The circuit when once closed as a result of the movement of the slide 28 will be maintained in such a condition until the 35 slide 28 is retracted to its normal position shown in Figure 2, thereby releasing the lug 37 and at the same time permitting the auxiliary arm 36, due to its inherent resiliency, to retract from engagement with the 40 casing 5.

It will be understood that while I have shown and described the switch embodying my invention in connection with a flashlight, the container of which is constructed 45 from metal, it is to be understood that the flashlight container may be constructed from fiber or other similar material, in which case a second conductor similar to that indicated by the numeral 22 may be 50 employed to electrically connect the auxiliary arm 36 with the zinc electrode of the battery when the slide 28 is so moved as to depress the arm 39.

Having thus described my invention, I 55 claim:

1. A safety switch comprising resilient main and auxiliary circuit closers adapted for series connection in an electric circuit, and movable means adapted to be moved in one direction to progressively move said closers to circuit closing positions and adapted to be moved in an opposite direction to permit said closers to progressively move to circuit opening positions as a result of their inherent resiliency.

2. A safety switch comprising a resilient circuit closer member having main and auxiliary circuit closers adapted for series connection in an electric circuit, and a switch actuating slide adapted to so cooperate with said circuit closer member as to facilitate movement of said main and auxiliary circuit closers one after the other to their respective circuit closing positions.

3. A safety switch comprising a circuit closer member having main and auxiliary circuit closers associated therewith and adapted for series connection in an electric circuit, a switch actuating member adapted to be so moved as to facilitate movement of said circuit closers one after the other to their respective circuit closing positions and thereafter retain the same in their respective circuit closing positions.

4. A safety switch comprising main and auxiliary circuit closers adapted for series connection in an electric circuit, a slidable switch actuating member adapted to be so moved as to move one of said closers to circuit closing position, and a circuit closer actuating element carried by said switch actuating member and adapted to be so moved upon the operation of said switch actuating member as to move the other of said closers to circuit closing position.

5. A safety switch comprising main and auxiliary circuit closers adapted for series connection in an electric circuit, a slidable switch actuating member adapted to be so moved as to move one of said closers to circuit closing position, and a circuit closer actuating element carried by said switch actuating member and adapted to be so moved upon the operation of said switch actuating member as to move the other of said closers to circuit closing position, said element being in the form of a cam member operatively connected with said switch actuating member.

6. A safety switch comprising a resilient circuit closer member provided at opposite ends with main and auxiliary circuit closers respectively, and a slidable switch actuating member adapted upon a predetermined movement thereof to effect a movement of one of said closers to circuit closing position and upon a further movement to effect a movement of the other of said closers to circuit closing position.

7. A safety switch comprising main and auxiliary resilient circuit closers, and a switch actuating member adapted to be so moved in one direction against the influence of said resilient circuit closers as to effect movement thereof to their respective circuit closing positions and further adapted to be moved in an opposite direction to permit said circuit closer to move as a result of their inherent resiliency to circuit opening positions.

8. A safety switch comprising a circuit closer member having main and auxiliary circuit closers associated therewith, a housing for said circuit closer member, and a switch actuating member carried by said housing, said switch actuating member being adapted to be so moved as to effect movement of said circuit closers to their respective circuit closing positions.
- 10 9. A safety switch comprising a resilient circuit closer member having main and auxiliary circuit closers associated therewith, a housing for said circuit closer member, a slide slidably mounted upon said housing and adapted to be moved a predetermined distance to effect a movement of one of said closers to circuit closing posi-

tion and further moved to effect a movement of the other of said closers to circuit closing position.

20

10. A safety switch comprising a resilient circuit closer member having main and auxiliary circuit closers associated therewith, a housing for said circuit closer member, a slide slidably mounted upon said housing and adapted to be moved to effect a movement of one of said closers to circuit closing position, and a cam member adapted to be bodily moved with said slide to effect a movement of the other of said closers to circuit closing position.
